US0D1094186S

(12) **United States Design Patent** (10) Patent No.: **US D1,094,186 S**
(45) Date of Patent: ** Sep. 23, 2025

(54) **AUTOMOBILE OR REPLICA THEREOF**

(71) Applicant: **ASTON MARTIN LAGONDA LIMITED**, Warwick (GB)

(72) Inventors: **Miles Nurnberger**, Warwick (GB);
Antonino Lo Re, Warwick (GB)

(73) Assignee: **Aston Martin Lagonda Limited**,
Gaydon (GB)

(**) Term: **15 Years**

(21) Appl. No.: **29/800,995**

(22) Filed: **Jul. 26, 2021**

(30) **Foreign Application Priority Data**

Jan. 27, 2021 (EM) 008416382-0001

(51) LOC (15) Cl. **12-08**

(52) U.S. Cl.
USPC **D12/88**

(58) **Field of Classification Search**

USPC D12/86, 88, 90, 91, 92, 164; D21/424,
D21/433, 434

CPC B62D 25/00; B62D 25/06; B62D 33/00;
B62D 35/00

See application file for complete search history.

(57) **CLAIM**

The ornamental design for an automobile or replica thereof, as shown and described.

DESCRIPTION

FIG. 1 is a rear elevation view of an automobile or replica thereof in accordance with the present design;

FIG. 2 is a front, right perspective view thereof;

FIG. 3 is a front elevation view thereof;

FIG. 4 is a left elevation view thereof;

FIG. 5 is a rear, left perspective view thereof;

FIG. 6 is a top view thereof; and,

FIG. 7 is a right elevation view thereof.

The portions of the automobile or replica thereof shown in evenly spaced broken lines depict environmental structures that form no part of the claimed design.

1 Claim, 7 Drawing Sheets
